OVEN DRAWER AND DOOR MECHANISM

George D. Wilkinson, Oak Park, and Nickolas Sheppel, Chicago, Ill., assignors to Cribben and Sexton Company, Chicago, Ill., a corporation of Illinois

Application October 13, 1939, Serial No. 299,360

9 Claims. (Cl. 126—340)

This invention relates to oven drawer and door mechanism and more particularly to structure by which the door of a range compartment may be opened part way to expose the interior without moving the drawer therein while further movement of the door causes the drawer to move forwardly.

An object of the present invention is to provide a range compartment drawer structure in which the drawer is adapted to be withdrawn through the action of the mechanism associated with the door, means being provided for permitting the door to be opened to a degree sufficient to expose the interior of the compartment without effecting movement of the drawer. A further object of the invention is to provide a range compartment with a drawer and closure therefor together with structure permitting the door to be opened partially without moving the drawer while further movement of the door causes the drawer to move forwardly in the compartment. Another object is to provide a structure in which the drawer may be removed from the compartment independently of the automatic moving mechanism and moved within the compartment independently of the automatic mechanism. Other specific objects and advantages will appear as the specification proceeds.

The invention is illustrated in the accompanying drawings in which Fig. 1 is a side elevational view of the oven with a portion of the wall broken away; Fig. 2 is a side elevational view of the oven partly broken away, with the side wall removed and with the door in open position; Fig. 3 is a fragmentary detail elevational view of a portion of the link mechanism used in moving the drawer in the oven; Fig. 4 is a fragmentary vertical sectional view taken along line 4 of Fig. 1; Fig. 5 is a fragmentary detail elevational view of the mechanism for engaging and moving the drawer within the oven; and Fig. 6 is a fragmentary detail elevational view of the rear portion of the oven drawer.

In the illustration given, A designates a range frame providing a compartment therein; B, a door closing the compartment; C, a drawer mounted within the compartment for withdrawal; and D, mechanism for causing the drawer to move after the door has been lowered a predetermined distance.

The range A may be of any suitable construction or type. It is sufficient for the purposes of the present invention that the range provide a space or compartment therein in which the drawer C may be mounted. Since range con-

struction is extremely old and well-known, a detailed description of the structure shown is believed unnecessary. The compartment may be a broiler oven compartment, a baking oven compartment, or any other compartment within the range. It is merely necessary that the range frame provide a space into which the drawer C be moved and with a front closure for the space.

The broiler drawer C may be of any suitable construction. In the illustration given, it is of old and well-known construction and need not be described in detail. The drawer is equipped with rollers 10 engaging a roller track 11 carried within the compartment by means of which the drawer can be readily reciprocated within the compartment. On one side the drawer C is provided with a pin 12 to bring about the movement of the drawer in the manner hereinafter described.

Door B may also be of any suitable construction, no novelty in the door being required. In the illustration given, the door is provided with a hinge 13 which is supported by bracket 14. Fixed to the door B at one side thereof is a curved actuating bar 15 which is used in conjunction with the mechanism D for bringing forward the drawer after the door passes a predetermined point.

The mechanism D may be constructed in a number of ways, one specific illustration being given in the drawings. An angle bar 16 is secured in the base portion of the range and along the lining portion at one side, as illustrated in Figs. 1, 2 and 4. Pivotedly secured to the vertical flange of the angle bar 16 is a link member 17. A spring 18 engages link 17 and a lug 19 with which the angle bar is provided and normally urges the link 17 in a backward direction. Pivotedly connected to the link 17 at its upper end is a small link 20 provided at its top with an inwardly extending pin 21. A washer 22 extends against the link 20 and over the pin 21, and is confined in position by a cotter pin 23, which extends through the pin 21. The pin 21 extends through a slot 24 in the compartment wall 25. The slot 24 is formed by turning inwardly the slot portions to form flanges 26. The inner end of the pin 21 is secured to a carriage plate 27, the plate 27 having outwardly turned flanges 28 slidably engaging the horizontal flanges 26 of the compartment wall 25. Pivotedly secured to the inner side of the carriage plate 27 is a latch plate 29, the pivot being indicated by the numeral 30. Plate 29 has a downwardly extending portion 31 having a perforated end engaged by

the hook of spring 32. The hook at the other end of the spring engages an opening in the flange 28 of plate 27.

At its upper side, the plate 29 is provided with inclined sides 33 which lead toward a deep slot 34, the slot 34 receiving the pin 12 of the drawer C.

Connected to the link 17 at a point above the lower end thereof is an actuating link 35. Link 35 carries at its lower end a pin 36 which engages an arcuate slot 37 in the link member 17, thus providing a lost motion connection between the two members. The upper end of the link 35 is pivotally connected at 38 to the bar 15 which is rigidly secured to the door B.

Operation

In the operation of the apparatus, when it is desired by the operator to look into the interior of the oven or other compartment, the door B may be dropped to the half way position illustrated in dotted lines in Fig. 2 without effecting any forward movement of the drawer C. In this movement, it will be noted that the curved bar 15 swings in a curved circuit which serves to raise the actuating link 35 but not to advance it. In this movement, the bar 15 is obliged to swing rearwardly a short distance in the initial movement, and this movement is compensated for by the arcuate slot 37 in the link 17. In other words, an actuating link 35 is permitted to move rearwardly a little without moving link 17 by reason of the slot 37 to permit the lever 15 to swing in a semicircular path from the lower position, as illustrated in Fig. 1, to the elevated position, as illustrated in full lines in Fig. 2. When the bar 17 has swung to the half way mark indicated in dotted lines in Fig. 2, it will be noted that for the first time, the link 35 is in a position to be drawn forwardly, carrying with it the links 17 and 20.

At the half way point just described, the operator may allow the door to stand, the link 35 extending in a straight line between the bar 15 and the lever 17, and in this position a full view of the interior of the compartment and drawer is obtained. Further, in this position, a fairly quick cooling of the interior of the compartment can be brought about without moving the drawer and its contents. Should the operator desire to have the drawer brought forward and partially withdrawn from the compartment, a further lowering of the door to the position shown in full lines in Fig. 2 brings the drawer C forward to the position illustrated. In bringing this about, the bar 15 attached to door B draws forwardly the link 35 and thereby brings links 17 and 20 to the position shown in full lines in Fig. 2. As link 20 is advanced, pin 21 carried thereby advances the carriage plate 27 and in turn the latch plate 29. The latch plate 29, which carries the drawer pin 12 within slot 34, causes the pin 12 to be advanced and thereby the drawer C.

Should the operator desire to withdraw the drawer to an even further extent, this can be done by raising the portion of the drawer adjacent the door so as to free the pin 12 from slot 34 of latch plate 29. The drawer may then be advanced with the rollers 10 remaining in the channels 11 until the drawer is removed from the oven, if this is desired. Likewise, if desired, the drawer may be raised to free the pin 12 from notch 34 and at the same time the drawer may be moved rearwardly of the latch plate 29. In

either of the latter positions, the drawer may be moved independently of the carriage. To replace it upon the carriage, it is merely necessary to move the drawer backwardly or forwardly, as the case may be, to bring the pin 12 against latch plate 29, in which event, the cam surfaces 33 cause the pivoted latch 29 to swing downwardly so that the pin 12 may enter the slot 34.

When it is desired to close the door and have the drawer C withdrawn, a slight upward movement of the door brings about this result, the returning movement being assisted by the spring 18.

It will be noted that the actuating structure 15 is extremely simple and compact and that it is housed within a side wall portion of the range, thus not occupying utility space.

The apparatus enables the operator to open the compartment to examine the contents without 20 moving the contents of the drawer and, likewise, to open the drawer the desired distance to cool the same without disturbing the contents by movement, but when a forward movement of the drawer is desired, this is selectively controlled 25 and brought about by a further downward movement of the door. At the same time, the drawer can be operated independently of the automatic door advancing mechanism by slight and fool-proof movements of the drawer itself.

It will be noted that if the drawer is raised 30 and pushed in for broiling with the door left open, or if the drawer is pushed to this position for any other reason, the mechanism picks up the drawer, when the door is closed, the spring-urged 35 latch plate 29 engaging the pin 12 of the drawer. The drawer will then operate with the door movement above described.

While in the foregoing description, we have set 40 forth certain details as illustrative of one mode in which the structure may be formed and operated, it will be understood that the details of such structure may be readily modified by those skilled in the art without departing from the spirit of our invention.

We wish it to be understood that we do not 45 desire to be limited to the exact details of construction shown and described, for obvious modifications will occur to a person skilled in the art.

We claim:

1. In combination with a range compartment, a door normally closing said compartment, a drawer mounted therein for withdrawal independent of the movement of said door, slidable means 55 mounted within said compartment and including a spring latch, means carried by said drawer, adapted to releasably engage said spring latch, and means associated with said door for effecting movement of said slidable means and latch member when the door is opened whereby when the latch is in engagement with the drawer the drawer will be moved by the opening of the door.

2. In combination with a range compartment, a door normally closing said compartment, a drawer mounted within said compartment for movement independent of said door, a member movably mounted in said compartment, means carried by said drawer for releasably engaging said member, and means associated with said door 70 for connecting the same to said member whereby the opening of said door effects movement of said drawer when the means carried by the drawer is in engagement with the member.

3. In combination with a range compartment, a

door normally closing said compartment, a drawer movably mounted within said compartment, a member slidably mounted at one side of said compartment, means for releasably connecting said drawer and said member, said drawer being mounted for withdrawal independent of the movement of the door when said connecting means are released, and mechanism for connecting said door with said member so that movement of the door effects movement of the drawer when the same is connected to the member.

4. In combination with a range compartment, a door normally closing said compartment, a drawer mounted for slidable longitudinal movement within said compartment, a member mounted for slidable longitudinal movement along one side of said compartment, mechanism connecting said member with said door so that movement of the door effects movement of the member, and means for releasably connecting said drawer and said member, said drawer being mounted for withdrawal from said compartment independent of the movement of said door when said connecting means are released, said means being operable to connect said drawer and said member when the member is moved by opening the door from closed position whereby movement of the door effects movement of the drawer.

5. In combination with a range compartment, a door normally closing said compartment, a drawer mounted therein for independent withdrawal, a member slidably mounted at one side of said compartment, means for releasably connecting said member and said drawer, and link mechanism connecting said door with said member so that movement of the door effects movement of the member, said mechanism including a pin and slot connection whereby said door may be partially opened before the member is moved.

6. In combination with a range compartment, a door normally closing said compartment, a drawer movably mounted within said compartment, a member slidably mounted for longitudinal movement along one side of said compartment, latch means carried by said member for releasably engaging said drawer, said drawer being mounted for longitudinal slidable movement within said compartment whereby the drawer may be withdrawn from the compartment independent of the movement of said door when the latch means is released, means for bringing said latch

means into connecting relation with said drawer when the member is moved within the compartment, and link mechanism connecting said door with said member so that movement of the door effects movement of the member.

7. In combination with a range compartment, a door normally closing said compartment, a drawer mounted within said compartment for independent withdrawal, a pin mounted on said drawer and projecting therefrom, a member slidably mounted on one side of said compartment adjacent said drawer, a notched latch member pivotally mounted on said slidably mounted member, said latch member being provided with cam surfaces adjacent the notch, spring means for yieldingly urging said notch toward the pin on said drawer whereby the slidably mounted member may be releasably connected to the drawer when the pin is received within the notch, and mechanism for connecting said door with said slidably mounted member so that movement of the door effects movement of the slidably mounted member.

8. In combination with a range compartment, a door normally closing said compartment, a drawer mounted for slidable horizontal movement within said compartment, the forward portion of said drawer being movable vertically within the compartment, said drawer being provided with a projecting member on one side thereof, a member slidably mounted for horizontal movement along the side of said compartment adjacent said side of the drawer, a latch member pivotally mounted on said member, said latch member having a vertical notch therein adapted to releasably receive said projecting member whereby the horizontally slidable member and the drawer are releasably connected, the portions of the latch adjacent said notch being inclined toward the mouth of the notch, spring means for yieldingly urging the notched portion of the latch into engagement with said projecting member, and link mechanism connecting said door with said horizontally slidable member so that movement of the door effects movement of the member.

9. A device as set forth in claim 8 wherein the link mechanism includes a pin and slot connection whereby the door may be partially opened before the drawer is moved.

GEORGE D. WILKINSON.
NICKOLAS SHEPPEL.
